(54) **SAW MILL, WIND**
(76) Inventor: **Jesse Springer**

Dear Springer.

Letter Patent dated 27th Dec 1815 & Recorded Jan 25th 1816.

The Schedule referred to in this Letter Patent and making part of the same, containing a description in the words of the inventor of the invention named & set forth in the Schedule.

The machinery of this saw mill consists of the following described parts, which are fitted together in wooden frames or galleries of suitable dimensions, as weather boarded and strengthened. The frame or gallery building may be made either of an octagonal frame or Hexagon, Pentagon or any other that may be found suitable across the interior of the (Building) towards the left is fitted a horizontal shaft turning on a quid gear in cross pieces at each end; these quid gears extend outward and form a crank that operates on a pitman which moves the motion of the saw, there is one of said cranks at each end of the shaft which moves the lever arm of two men in opposite directions.

From one end of the shaft is a Trunnion head and on the opposite side of the shaft near the end is fitted a balanced wheel of suitable size.

Just over the said shaft is placed a horizontal beam directly at right angles with the shaft and the ends are framed in the uprights of the building. In the center of said beam which is immediately over the center of the shaft is fitted a quid gear which turns the lever arm of a perpendicular shaft called the center shaft the pinion on the upper part of this shaft turns an across beam fitted across the center of the revolving top frames.

Near the lower end of said shaft is fitted a horizontal cog-wheel the cog of which runs into the rams of the trunnion head. Two small cog-wheels which is fitted on the same shaft, a h. cog-wheel turned head the sound of which is set into the cog of the larger main cog-wheel which is fitted on a horizontal shaft across the top.

of the top frame, the said shaft projects out from the building on in other parts, & receives at the arms end parts which are operated on by the wind, and give motion to the machinery at the bottom of the frame or building under the cranks before mentioned in this (the skins) quays which receive through them the logs to be turned.) A perpendicular shaft is suspended from the center cog wheel, attached to the Wag wheel that moves the carriage that carries the back after the calf is sawed.
